VALVE MOUNTING FOR REFRIGERATOR COMPRESSORS

Leland G. Knapp, Chicago, Ill., assignor to Montgomery Ward & Co., Incorporated, Chicago, Ill., a corporation of Illinois

Application June 25, 1934, Serial No. 732,226

5 Claims. (Cl. 230—228)

The present invention is related to compressors for domestic or household refrigerators, and is concerned particularly with the valves for controlling the discharge of the refrigerant from the 5 compressor cylinder.

The object of the invention is to provide a novel mounting for the discharge valve and its deck so as to insure proper retention of the deck in the cylinder head, and prevent displacement of the 10 valve deck from its applied position. The invention, therefore, overcomes the necessity of frequently overhauling the compressor to repair the valve and replace its deck and the resultant interruption in the operation and use of the refrigerator.

A further object of the invention is to so construct the valve deck and relate the same to the compressor head that the valve deck readily may be removed or replaced when occasion requires.

20 Other objects and advantages sought to be attained will appear as the nature of the improvements is better understood, the invention consisting in the novel construction, combination and arrangement of parts hereinafter fully described, 25 illustrated in the accompanying drawing, and finally pointed out in the appended claims.

In the drawing,

Fig. 1 is a longitudinal sectional view of the cylinder of a refrigerator compressor provided 30 with a valve mounting constructed in accordance with the present invention, the line of section being as at 1—1, Fig. 2; and

Fig. 2 is a transverse sectional view of the cylinder as on the line 2—2, Fig. 1.

35 Referring now in detail to the accompanying drawing, the numeral 10 designates the cylinder of a compressor of the type commonly employed in domestic or household refrigerators, the same being provided with the usual piston 11, and also 40 an inlet port 12 for admitting the refrigerant to the bore of the cylinder. The latter also is provided with an outlet port 13 through which the compressed refrigerant is discharged from the cylinder.

45 Associated with the end of the cylinder 10 is the customary head 14, provided with radiating fins 15 to assist in the cooling of the head, and the latter is connected to and held upon the open end of the cylinder 10 by means of a series of 50 fastening bolts 16, generally illustrated in Fig. 2.

Within the head 14 is a valve chamber 17 aligned with the bore of the cylinder 10, and in communication with the valve chamber is a spring-receiving chamber 18. From the chamber 55 18 an exhaust port 19 extends so as to communi-

cate with the outlet 13 of the cylinder 10, thereby establishing a path of flow for the compressed refrigerant from the valve chamber 17 and the spring-receiving chamber 18 to the outlet 13.

A valve 20, in the form of a disk, is located in the chamber 17, which valve is of slightly less diameter than the diameter of the chamber, and a coil spring 21 is seated in the spring-receiving chamber 18, one end thereof abutting against the valve 20, and the other end being seated against the head 14, the spring 21 thereby exerting its pressure to maintain the valve 20 in contact with its seat. The latter is constituted by an annular bead 22 which is formed on a valve deck 23. This deck also is in the form of a disk, and the same is 15 provided with a plurality of ports 24 which lie within the area defined by the annular bead 22. The ports 24 afford communication between the bore of the cylinder 10 and the valve chamber 17, and under the action of the piston 11 the compressed refrigerant passes through the ports 24 to the valve chamber 17, the valve 20 being thereby unseated against the pressure of the spring 21, and permitting the compressed refrigerant to flow around the edges of the valve 20 into the valve 25 chamber 17, the spring-receiving chamber 18, and out through the duct 19 to the outlet 13.

In refrigerator compressors of the construction and type above described, it is essential that the valve deck be retained on the cylinder head and 30 prevented from displacement from its applied position thereon. Otherwise, it is frequently necessary to overhaul the compressor in order to repair the valve and replace the deck which may become displaced from its position on the cylinder 35 head, all of which results in interruption in the use of the refrigerator and its operation. In this connection it is to be observed that the valve deck 23 has a diameter which is coextensive with the diameter of the head 14, and also with the 40 end of the cylinder 10 to which the head 14 is applied. It is also provided with a port 25 designed to register with the outlet 13 of the cylinder and with which port the duct 19 likewise 45 communicates. That the valve deck may be retained on the cylinder head and prevented from displacement therefrom, a plurality of fastening pins 26 is employed. These fastening pins, preferably, are brass escutcheon pins the heads of which are round, and said pins are received by a 50 plurality of registering holes 27 which are drilled in the cylinder head 14 and in the valve deck 23. They are positioned adjacent the marginal portions of both the head 14 and the valve deck 23. The outer ends of the holes 27 which ter- 55

minate in the face of the valve deck are countersunk. In mounting the valve deck 23 on the cylinder head 14 the pins 26 are driven into the holes 27 with a snug fit and the round heads of the 5 pins are peened down so as to fit within the countersinks of the holes 27, thus securely fastening the valve deck 23 onto the cylinder head 14, and preventing displacement of the valve deck. Removal of the latter may be effected 10 by boring out the pins 26, should repair or replacement be required. After the valve deck 23 has been secured onto the cylinder head 14 by the pins 26 in the manner described, the surface of the valve deck is ground by any suitable 15 means so as to bring that surface and the pins into the same plane to permit proper application of the head 14 to the cylinder 10.

A common packing gasket 28 is interposed between the valve deck 23 and the cylinder 10, and 20 a similar gasket 29 is interposed between the head 14 and the valve deck 23 to obtain tight joints between these parts.

By the employment of the herein described invention there is provided a novel mounting for 25 the discharge valve and its deck which insures proper retention of the deck on the cylinder head and prevents displacement of the valve deck from its applied position. The deck 23 is securely and firmly held to its seat on the head 14, and 30 necessity for frequently overhauling the compressor to repair the valve and replace its seat is overcome.

While the invention has been described particularly with reference to compressors for domestic or household refrigerators, it is apparent that its use is not restricted to this field, but the same is capable of employment in and adaptation to compressors of other types where it is desired to maintain the decks of the valves in 40 proper applied position.

The invention herein described and claimed is to be distinguished from the subject-matter of my co-pending application Serial No. 732,225, filed June 25, 1934, wherein the valve deck is set 45 within that face of the cylinder head which contacts the cylinder, the outer face of the valve deck lying flush with the face of the head. In the present disclosure the valve deck is co-extensive in diameter with the diameter of both the 50 compressor head and compressor cylinder and is positioned therebetween.

I claim:

1. In a valve mounting of the class described, the combination with a compressor head having 55 a valve chamber, and a valve arranged in said chamber, of a valve deck arranged over the valve chamber of the compressor head and providing a seat for said valve, the head being provided with a series of recesses, and fastening pins 60 fitted into said recesses and driven therein to be applied rigidly to the head, said fastening pins also passing through the valve deck and being expanded into engagement with the valve deck to hold the latter in applied position on the cylinder head.

2. In a valve mounting of the class described, the combination with a compressor head having a valve chamber and a valve arranged in said chamber, of a valve deck arranged over the valve chamber of the compressor head and providing 5 a seat for said valve, the head being provided with a series of recesses arranged adjacent to the edges thereof, and fastening pins fitted into said recesses and driven therein to be applied rigidly to the head, said fastening pins also passing through the valve deck and being expanded into engagement with the valve deck to hold the latter in applied position on the cylinder head. 10

3. In a valve mounting of the class described, the combination with a compressor head having a valve chamber, and a valve arranged in said chamber, of a valve deck arranged over the valve chamber of the compressor head and providing with a series of recesses arranged adjacent to the edges thereof, and headed fastening pins fitted into said recesses and driven therein to be applied rigidly to the head, said fastening pins also passing through the valve deck, the heads of said fastening pins being expanded into engagement with the valve deck to hold the latter in applied position on the cylinder head. 15

4. In a valve mounting of the class described, the combination with a compressor head having a valve chamber, and a valve arranged in said chamber, of a valve deck arranged over the valve chamber of the compressor head and providing a seat for said valve, the head and the valve deck being provided with a series of registering 30 recesses arranged adjacent to the edges thereof, the outer ends of said recesses terminating in countersinks formed in the face of the valve deck, and headed fastening pins fitted into said recesses and driven therein to be applied rigidly to the head, said fastening pins also passing 35 through the valve deck, the heads of said fastening pins being expanded into engagement with the countersinks of the valve deck to hold the valve deck in applied position on the cylinder head. 40

5. In a valve mounting of the class described, the combination with a compressor head having a valve chamber, and a valve arranged in said chamber, of a valve deck arranged over the valve chamber of the compressor head and providing 50 a seat for said valve, the head and the valve deck being provided with a series of registering recesses arranged adjacent to the edges thereof, the ends of the recesses at the face of the valve deck which is adapted to contact the compressor cylinder being formed with countersinks, and headed fastening pins fitted into said recesses of the head and driven therein to be applied rigidly to the head, said fastening pins also passing through the registering recesses of the valve deck, the heads of said fastening pins being expanded into engagement with the countersinks of the valve deck to hold the valve deck in applied position on the cylinder head. 55
